(57) **CLAIM**

The ornamental design for an instrument for pulling and twisting a wire, as shown and described.

DESCRIPTION

FIG. 1 bottom perspective view of the instrument for pulling and twisting a wire, showing our new design;

FIG. 2 is a top plan view of FIG. 1;

FIG. 3 is a bottom plan view of FIG. 1;

FIG. 4 is a front elevational view of FIG. 1, on a larger scale;

FIG. 5 is a right side elevational view of FIG. 4, on a reduced scale.

FIG. 6 is rear elevational view of FIG. 1, on a larger scale;

FIG. 7 is a right side elevational view of FIG. 6; and,
FIG. 8 is a sectional view taken along the plane designated by the line 8—8 on FIG. 7, on a reduced scale.
